UNITED STATES PATENT OFFICE

CARL HELLWIG, OF CALI, COLOMBIA

AUTOMATIC RAILWAY CAR COUPLING

Application filed December 29, 1930, Serial No. 505,397, and in Germany September 17, 1929.

This invention relates to certain new and useful improvements in automatic railway car couplings used for automatically coupling one car of a railway train to that of another. The object is to produce an automatic railway car coupling which is absolutely safe in operation, and may be manufactured with comparatively low costs, as will be hereinafter fully set forth, claimed 10 and illustrated in the accompanying drawings.

Fig. 1 is a front view, and

Fig. 2 a plan of the coupling connected with the end of a car, and engaged by the 15 draw-head of another car.

Fig. 3 is a similar plan view, in a position in which the draw-head is disengaged.

Fig. 4 is a side view of the coupling.

The principal parts of the railway car 20 coupling consist of two rotatable toothed or corrugated coupling members *a* journaled rotatably on strong, rigid bolts *b* in a frame *c* firmly mounted on the end of the car. This frame *c* comprises two lateral arms *d* and *f*, 25 on the upper ends of which a locking rail or bar is adapted to slide. On the arm *f* the locking bar *g* is guided by a threaded stud *h* projecting through a slot *h'* of the bar *g* and carrying a nut *h*². The locking bar *g* is more- 30 over provided with slots *i* through which project studs *b'* formed by the reduced ends of the bolts *b*, which reduced ends are threaded and provided with nuts *b*². The arm *d* of the frame *c* is bifurcated and between the 35 shanks *d'* and *d*² of the bifurcation the bar *g* is laterally guided. Studs *k* mounted on the upper faces of the coupling members *d* engage links *m* which are pivoted by a stud *n* to the locking bar *g* to form a linkage be- 40 tween the coupling members *a* and the locking bar *g*. On one of the shanks (*d'*) of the bifurcated arm *d* a lever *o* forming a rotatable latch is rotatably mounted, adapted to engage either by itself or by a shoulder *o'* a recess *p* of the bar *g* in locking position of the coupling, Fig. 2. A spring *q* attached with one end to the arm *d* and with its other end to the latch *o* tends to keep the latch down on the bar *g* so as to force it into the recess *p* when the coupling is closed. The sec-

ond shank *d*² of the bifurcated arm *d* serves for guiding the free end *o*² of the latch *o*, which by a rod *r* is connected with an arm of a two-armed lever *s*, the other arm of which being constructed as a handle, by the aid of which the latch *o* may be raised to release the locking bar *g*.

The draw-head *t* of the other car is provided with corrugations *u*, thus forming one member of the coupling. These corrugations *u* correspond with the corrugations or teeth *v* of the coupling members *a*.

When two cars approach one another the coupling member or draw-head *t* engages in between the corrugations *v* of the coupling members *a*, which thereupon rotate in the direction of the arrows shown in Fig. 3. When the rotation is accomplished to such an extent as is shown in Fig. 2, the links *m* having effected a sliding movement of the locking bar *g*, the latch *o* by the action of the spring *q* drops into a gap *p* and thus locks the coupling in this position, Fig. 2. Any pulling action of the draw-head *t* cannot result in a release or opening of the coupling. When such release is to be carried out, the handle *s* must be pressed down thereby lifting the latch *o* upwardly, so as to disengage the bar *g*. When now a pull is exerted the draw-head *t* will be released from engagement of the coupling members *a* which will rotate back into the position shown in Fig. 3 the links *m* and the bar *g* no longer preventing such movement.

The locking bar *g* which is made sufficiently strong and broad, may be provided with gaps *k'* into which the studs *k* may engage when the coupling is released. This will prevent the locking bar *g* to slip into any undesired position giving it a good hold.

For allowing irregularities in the dimensions of the cars or of the position of the coupling member or draw-head *t* and also for allowing variations when passing curves the frame *c* is not firmly attached to the end of the car but is only guided on a fixed wall or plate *w* and connected with the car by chains *x*, which may be held taut by the spring *y*. By such means any differences

with regard to the straight line are well overcome.

I claim:

1. An automatic railway car coupling comprising two rotatable coupling members and a cooperating coupling member adapted to engage said rotatable coupling members when the car on which the cooperating coupling member is mounted approaches the car on which said rotatable coupling members are mounted, a locking bar, links connecting the last named members with said locking bar and a latch adapted to engage and lock said locking bar in coupling position of the coupling members.
2. An automatic railway car coupling comprising two rotatable coupling members and a cooperating coupling member adapted to engage said rotatable coupling members when the car on which the cooperating coupling member is mounted approaches the car on which said rotatable coupling members are mounted, a locking bar arranged slidably on the pivots of the rotatable coupling members, links connecting the last named members with said locking bar and a latch adapted to engage and lock said locking bar in coupling position of the coupling members.

In testimony whereof I have signed my name to this specification.

CARL HELLWIG.
